UNITED STATES PATENT OFFICE

2,612,810

COMBINATION SETTER FOR ORGANS

Earle L. Kent, Elkhart, Ind., assignor to C. G. Conn Ltd., Elkhart, Ind., a corporation of Indiana

Application April 21, 1948, Serial No. 22,430

4 Claims. (Cl. 84—345)

1

My invention relates to a combination setter for use with an organ or the like and which is particularly suitable for use with an electric organ.

It is frequently necessary to set an organ to play tones corresponding to actuation of a particular combination of stop tablets at successive times during a relatively short time interval. Thus, for example, the organist may desire repeatedly to play a combination of the swell 8' diapason and 8' flute. To facilitate this operation, it is desirable to provide a single combination piston or element which may be actuated to set the stop tablets as required to produce the combination tone.

However, it is not possible to provide a separate piston for every combination of stop tablets desired to be set in the foregoing manner since the number of combinations is so great that an organ of prohibitive size would be necessary. In accordance with the present invention, this problem is overcome by providing capture type mechanism for this purpose, the specific mechanism shown comprising a plurality of axially shiftable rods each having a number of swingable contact fingers. Each rod has an associated combination piston or element which, when depressed, causes a preselected tone combination to sound when the organ is played. Selection of the desired combination of stop tablets is achieved by depressing the combination piston and the stop tablets corresponding to the desired tones and simultaneously depressing a common setting element or button.

The present invention further resides in providing means by which the combination of stop tablet settings, corresponding to actuation of each of the several combination pistons or elements, may be fixed by depressing the corresponding stop tablets and then depressing a suitable common setting button or element. This permits the organist to preset the mechanism in a manner to which he is accustomed by reason of his ability to play the organ, and it is unnecessary to learn a new set of controls for the purpose of presetting the combinations.

The term "capture" type combination setter is used herein to designate mechanism whereby a selected combination of stop tablet settings may be "captured" for future resetting upon appropriate actuation of a combination piston.

It is, accordingly, a general object of the present invention to provide an improved capture type stop tablet combination setter for an organ.

More specifically, it is an object of the present

2

invention to provide an improved combination setter for an organ which may be preset by depressing the organ stop tablets corresponding to the selected tones to be played by the organ.

5 Another object of the present invention is to provide an improved capture type combination setter for an organ and in which several preset stop tablet combinations may be selectively reset by actuation of their respective combination pistons or simultaneously reset by actuation of a common combination piston or element.

Further, it is an object of the present invention to provide an improved combination setter for an organ or the like which is simple in construction and reliable in operation to the end that it may be inexpensively constructed and requires little maintenance.

20 The novel features which I believe to be characteristic of my invention are set forth with particularity in the appended claims. My invention, itself, however, both as to its organization and method of operation, together with further objects and advantages thereof, may best be understood by reference to the following description taken in connection with the accompanying drawing in which:

25 Figure 1 is a diagrammatic isometric view showing a two-element combination setter constructed in accordance with the principles of the present invention;

30 Figure 2 is a greatly enlarged fragmentary isometric view of one of the operating rods and a finger mounted thereon;

35 Figure 3 is a view like Fig. 2 but showing the operating rod in the lifted or engaging position and the setting bar in co-acting relationship therewith;

40 Figures 4a and 4b are fragmentary diagrammatic elevational views showing the operation of the setting bar mechanism; and

45 Figure 5 is a fragmentary view of a modified embodiment of the present invention incorporating means simultaneously to reproduce a plurality of tone combinations.

50 Referring now to Fig. 1 there is shown at 10 and 12 a pair of vertically disposed axially shiftable operating rods. Each of these rods is of material having good electrical conductivity, such as, for example, aluminum. Bearings 11 and 13 are provided to sustain the rods in a vertical position for up and down axial shifting movements, cups 15 and 17 being provided to limit the downward movements. A pair of lift coils or solenoids 14 and 16 are disposed about the upper

55 portions of each of these rods and operate when

energized by suitable current flow, to lift these rods against the action of gravity, the rod 10 terminating in magnetic portion 10a and rod 12 terminating in magnetic portion 12a for coaction with the solenoids 14 and 16, respectively. The rods 10 and 12 are selectively lifted by depression of the combination pistons or elements 18 and 20 respectively, these pistons completing the electric circuits which may be traced from ground through the source 22, the element 18 or 20, and the winding 14 or 16 back to the ground. Thus, actuating the elements 18 or 20 operates selectively to lift the rods 10 and 12.

A plurality of lengthy horizontal fingers 24, 26, 28, and 30 are swingably supported on the rods 10 and 12 for axial shifting movements with these rods. The mechanism for this purpose is described in further detail hereafter. These fingers are constructed of steel or other suitable conducting material.

A pair of fixed contact bars are associated with each tier of horizontally aligned fingers. The contact bars associated with the fingers 26 and 28 are indicated at 32 and 34, whereas the contact bars associated with the fingers 24 and 30 are indicated at 36 and 38.

The stationary contact bars 32, 34, 36, and 38 each support appropriate contact buttons 32a, 32b, 34a, etc. These buttons are positioned for engagement by the fingers 24, 26, 28, and 30 when the appropriate operating rods are axially lifted by energization of the solenoids 14 and 16. The contact buttons 32a, 32b, 36a and 36b are engaged by the fingers when in the left hand positions as seen in Figure 1 and the contact buttons 34a, 34b, 38a and 38b are engaged when the fingers are swung to the right hand positions as seen in that figure.

In addition to the fixed contact buttons which are cooperatively associated with the fingers, there are provided axially shiftable setting bars 40 and 42, each of which is horizontally disposed and has a plurality of notches 40a, 40b, 42a and 42b for engagement with the appropriate contact fingers when the operating rods 10 and 12 are in the lifted positions corresponding to energization of the solenoids 14 and 16.

The setting bars 40 and 42 are each biased to intermediate or central positions by the opposed springs 44, 46, 48, and 50 to cause these bars to assume intermediate positions when released. Solenoids 52, 54, 56 and 58 are disposed at the opposite ends of these bars and the end of each bar terminates in a magnetic plunger portion 40c, 40d, 42c and 42d, which cooperates with the associated solenoid to produce axial shifting movements of the corresponding setting bar. When solenoids 52 and 56 are energized, the bars 40 and 42 are shifted in the left-hand direction, as seen in Fig. 1, whereas when the solenoids 54 and 58 are energized, these bars are shifted in the right-hand direction, as seen in that figure.

In the view of Fig. 1, there are shown two stop tablets, one being generally indicated at 60 and the other being indicated generally at 62. Each of these comprises a pivotally supported key portion 60a and 62a, respectively, which executes selective switching action against the contacts 60b and 60c and 62b and 62c respectively. The magnetic arms 60d and 62d form extensions of the key portions 60a and 62a. Interconnecting elements (not shown) are provided to energize the organ circuits in accord with the setting of stop tablets 60 and 62 to produce the desired tone combinations when the organ is played.

Referring now to the stop tablet 60, it will be apparent that solenoids 60e and 60f are positioned on opposite sides of the magnetic portion 60d and are thus operable when energized to raise or lower the portion 60d to tilt the key 60a in the same manner as when manually operated. Similarly, solenoids 62e and 62f are positioned on opposite sides of the magnetic portion 62d of stop tablet 62 to operate that key in accordance with the energization thereof.

The solenoids 60e and 60f are selectively energized from the battery 22 by two separate circuits, one corresponding to combination piston 18 and the other corresponding to combination piston 20. The former circuit may be traced from battery 22 through conductor 66 and lift-solenoid 14 which serves to raise the operating rod 10 to cause finger 26 selectively to engage contact 32a or contact 34a. The solenoid 60e or 60f is thereby energized through the circuit which may be traced from contact 32a or contact 34a, through the finger 26 and rod 10 to the flexible pigtail conductor 68. That conductor is connected to conductor 70 which, in turn, connects to conductor 64 through the lower normally closed switch element 72b of the setter element 72 and the combination piston 18.

The other circuit for selectively energizing solenoids 60e and 60f is set up by axially shifting operating rod 12 until the finger 28 engages contact buttons 32b and 34b, this being accomplished by energization of solenoid 16 by actuation of combination piston 20. In this case, the energizing circuit to solenoid 60e or 60f may be traced from the appropriate contact element 32b or 34b, finger 28, rod 12, and pigtail connection 74, to conductor 70. From conductor 70, the circuit may further be traced through lower switch element 72b of setter element 72 and combination piston 20 to battery 22.

The solenoids 62e and 62f are selectively energized through the contact buttons 36a and 38a when operating rod 10 is lifted by energization of solenoid 14 or through contact buttons 36b or 38b when operating rod 12 is lifted by energization of solenoid 16. This establishes circuit connections like those previously described with reference to the fingers 26 and 28 and which operate to actuate the stop tablet 62.

It will be obvious from the foregoing description that the stop tablets 60 and 62 are selectively operated when the operating rods 10 and 12 are lifted. The particular stop tablets energized are determined by the positions of the fingers 24, 26, 28, and 30 as they are swung about the corresponding operating rods. In accordance with the present invention these fingers are swung to predetermined positions to preselect the combination of stop tablets corresponding to actuation of the combination pistons 18 and 20.

When the operating rod 10 is lifted by energizing solenoid 14, the fingers 24 and 26 are raised to positions in registry with the notches 40a and 42a of the setting bars 40 and 42. When operating rod 10 is in this condition, shifting the rod 40, for example, along its axis causes corresponding swinging movements of the finger 26 as it is engaged by the edge portions of the notch 40a. This movement is determined by the energization of the selected solenoid 52 or 54 which overcomes the bias of springs 44 and 46 to shift bar 40 from the neutral position.

The operation of the setter bars may best be understood by reference to Figures 4a and 4b which are enlarged side elevational views of the

portion of the bar 40 adjacent notch 40a. As will be evident from Figure 4a which shows the bar 40 in the neutral position, the notch 40a is of sufficient width to register with the finger 26 regardless of the position of that finger as it is swung about the rod 10. This will be apparent from the extreme positions of this finger as indicated by the dotted lines of that figure.

In Figure 4b the bar 40 is shown in the extreme left hand position. It will be apparent that in this position the edge of notch 40a bottoms against the finger 26 to swing that finger to the left hand position for engagement with the contact button 32a, Figure 1.

The function of the setter element 72 and the contact elements 60b and 60c is selectively to energize the solenoids 52 and 54 when the corresponding combination piston 18 or 20 is actuated. The energizing circuit for solenoid 54, for example, may be traced from the ground connection to the key 60 through contact element 60c, solenoid 54, and conductor 16 to the upper contact element 72a of setter element 72. When the setter element is depressed, contact button 72a is in electrical conducting relationship with central finger 72b which is connected to combination piston 18 by conductor 18 and which is, in turn, selectively connected through that element to conductor 64 and battery 22. An energizing circuit for solenoid 54 may be traced in like manner through the combination piston 20. Similarly, solenoid 52 is energized by the circuit which may be traced through contact element 60b to ground and through conductor 80 and setter element 72 to battery 22 the latter connection being selectively established by combination piston 18 or combination piston 20.

From the foregoing, it will be observed that the setting bar 40 is shifted by solenoids 52 and 54 when the setter element 72 and the combination piston 18 or the combination piston 20 are simultaneously actuated, and that the direction of shift of bar 40 is determined by the position of key 60. It will further be observed that when combination piston 18 is actuated, the operating rod 10 is lifted to position finger 26 for engagement with notch 40a of setting bar 40 and when player element 20 is actuated, the operating rod 12 is lifted to position finger 28 for engagement with notch 40b of setting bar 40.

The solenoids 56 and 58 which operate to shift the setting bar 42 are connected to the contacts 62b and 62c of key 62 in the same manner as are the solenoids 52 and 54 with respect to contact elements 60b and 60c. Consequently, the bar 42 acts to swing the fingers 24 and 30 in accord with the position of the key 62 at the time setter element 72 is actuated and the selected combination piston 18 or 20 is actuated.

The setter element 72 performs the further function of de-energizing solenoids 60e, 60f, 62e and 62f when the combinations are being established. This operation is achieved by contact button 72c which is disconnected from finger 72d when the setter element 72 is actuated, thereby breaking the energizing circuit for these solenoids by interrupting the connection between operating rods 10 and 12 and the battery 22. This prevents energization of the coils 60e, 60f, 62e, and 62f when the combination pistons are depressed during the setting operation.

From the foregoing description, it will be evident that when the organist desires to set up a predetermined combination of stop tablets to be set up upon actuation of combination pistons 18

or 20, he merely sets up the stop tablet combination desired to be "captured" and then depresses setter element 72 and the combination piston 18 or 20, depending upon which combination piston he desires to establish the combination of stop tablets. If at any future time he desires to set up this combination of stop tablets without having to depress the corresponding stop tablets, he merely actuates the corresponding element 18 or 20. Thus, the mechanism of the present invention operates to provide capture of the stop tablet setting corresponding to the initial setting of the stop tablets and reproduces that setting upon actuation of the corresponding combination piston.

In Figure 1, the combination piston 18, the stop tablet 60, and the setter element 72 are shown in actuated position, thereby lifting rod 10 and swinging fingers 26 and 24 to the left and right respectively. The rod 12 is in the unlifted position and hence allows fingers 28 to drop out of registry with the corresponding notches in bars 40 and 42.

Figures 2 and 3 are enlarged fragmentary views of the operating rod 10 and the finger 26. As will be evident from Fig. 2, the finger 26 is attached to the sleeve 82 which is freely sustained on the shaft 10. This sleeve rests on the fixed sleeve 84 which is held in fixed axial position relative to rod 10 by set-screw 84a. The dotted lines of Fig. 2 show the finger 26 swung to position for engagement with the contact element 34a (Figure 1).

In Figure 3, the solid lines show the finger 26 in the lifted position for engagement with the notch 40a of the setting bar 40, while the dotted lines indicate the normal position of the finger 26 when the rod is in the position corresponding to de-energization of the solenoid 14.

When the fingers 24, 26, 28, or 30 are once swung to preselected positions, the organ may be played indefinitely without altering these positions since friction between the sleeves 82 and the supporting collars 84 opposes swinging movements of these elements.

In accordance with a modification of the present invention a plurality of operating rods are arranged to be actuated selectively by their individual combination pistons or simultaneously by a single combination piston. One arrangement for this purpose is shown in Figure 5 where a plurality of lift coils are indicated at 100, 102, 104, 106, 108, 110, 112, 114, 116 and 118. Each of these coils is operatively associated with an operating rod in the same manner as the lift coils 14 and 16, Figure 1.

In addition to the main lift coils 100 to 118, there are supplementary lift coils associated with the various operating rods. In Figure 5 only coils 120 and 121 are of this type although it will be understood that many of these may be provided.

As will be evident from Figure 5, the combination piston 18 energizes lift coils 100, 104, 108 and 112 simultaneously by connecting the same to the battery 22. However, the combination piston 20 only energizes the single lift coil 120. Similarly combination piston 21 energizes the single lift coil 121. Thus when combination piston 20 or 21 is actuated, only the settings controlled by shifting of the operating rod controlled by coil 120 or coil 121 are produced whereas when combination piston 18 is actuated the settings controlled by shifting of the four operat-

ing rods controlled by coils 100, 104, 108 and 112 are produced.

The operating rods controlled by the coils 100, 102 etc., Figure 5 may be separated in space and in addition, may control different stop tablets. Hence even though actuation of one of the operating rods controlled by a particular combination piston may not produce the necessary setting, the various operating rods in combination are capable of achieving this purpose. Moreover the use of a single combination piston 18 to actuate solenoids 100, 102, 104, 108 and 112 renders it possible to produce a selected complex coupling combination without actuating a plurality of independent stop tablets.

It will be apparent from the foregoing that in the apparatus of the present invention fingers 24, 26, 28 and 30 are movable in two senses, one constituting shifting motion with the corresponding operating rod and the other constituting swinging motion about that rod. Each finger is preset as to the latter motion by the corresponding setter bar 40 or 42 and all of the fingers on each operating rod are moved in the former sense by the shifting movements thereof when the associated player element is actuated.

In a practical organ it is convenient to provide a plurality of combination pistons 18 and 20 to provide for storage of a large number of stop tablet settings. However, a single setter element 72 may be common to all of these combination pistons, the setter element having as many switch elements as are required to satisfy the requirements of the combination pistons.

In the appended claim I have used the term capture type operating mechanism to denote mechanism such as that of operating rods 10 and 12 and which establishes a predetermined condition, such as the positions of fingers 24, 26, 28 and 30, to be retained for future use in resetting the stop tablets.

While elements 60 and 62 are referred to herein as swingable stop tablets, it will, of course, be understood that these may be any suitable type of electrically controlled switches such as, for example, plunger switches or the like. Moreover, the combination 18 and 20 may be any suitable switches such as, for example, key operated switches.

While I have shown particular embodiments of my invention, it will of course be understood that I do not wish to be limited thereto since many modifications both in the circuit arrangement and in the structures disclosed may be made without departing from the spirit and scope of my invention. I, of course, contemplate by the appended claims to cover any such modifications as fall within the true spirit and scope of my invention.

I claim:

1. A combination setter to capture a setting of stop tablets in an organ or the like comprising in combination, a setter element, a plurality of combination pistons, a plurality of capture type operating mechanisms, one corresponding to each of said combination pistons and operative in response to actuation of said setter element and the corresponding combination piston to establish a predetermined condition in accord with the condition of stop tablets at that time, and means operative in response to actuation of each of said combination pistons to reset said stop tablets in

accord with said condition of the corresponding operating mechanism.

2. A combination setter to capture a setting of stop tablets in an organ or the like comprising in combination, a setter element, a plurality of combination pistons, a plurality of capture type operating mechanisms, one corresponding to each of said combination pistons and operative in response to actuation of said setter element and the corresponding combination piston to establish a predetermined condition in accord with the condition of stop tablets at that time, means operative in response to actuation of each of said combination pistons to reset said stop tablets in accord with said condition of the corresponding operating mechanism, and a supplementary combination piston selectively operable to actuate a plurality of said operating mechanisms.

3. In a combination setter to capture a setting of stop tablets in an organ or the like, the improvement which comprises a plurality of sets of members, one member of each set corresponding to each of said stop tablets, said members each being movable in two senses and operable to actuate said stop tablets when in predetermined position in each of said senses, a manually operable combination piston associated with each set of members, means operable in response to actuation of said setter element and the combination piston corresponding to the set of which each member forms a part to move said member to said predetermined position in one sense when the corresponding stop tablet is actuated, and means operable in response to actuation of said combination pistons simultaneously to move all the members of the corresponding set to said predetermined position in the other sense.

4. In a combination setter to capture a setting of stop tablets in an organ or the like, the improvement which comprises a plurality of sets of members, one member of each set corresponding to each of said stop tablets, said members each being movable in two senses and operable to actuate said stop tablets when in predetermined position in each of said senses, a manually operable combination piston associated with each set of members, means operable in response to actuation of said setter element and the combination piston corresponding to the set of which each member forms a part to move that member to said predetermined position in one sense when the corresponding stop tablet is actuated, and means operable in response to actuation of said combination pistons simultaneously to move all the members of the corresponding set to said predetermined position in the other sense, said setter element including means operable to block operation of said last means when said setter element is actuated.

EARLE L. KENT.
